UNITED STATES PATENT OFFICE

WALTER F. ROGERS, OF CICERO, ILLINOIS, ASSIGNOR TO CROWN STOVE WORKS, OF CICERO, ILLINOIS, A CORPORATION OF ILLINOIS

DESIGN FOR A GAS STOVE

Application filed September 22, 1930. Serial No. 37,035. Term of patent 14 years.

To all whom it may concern:

Be it known that I, WALTER F. ROGERS, a citizen of the United States, residing at Cicero, in the county of Cook and State of Illinois, have invented a new, original, and ornamental Design for Gas Stoves, of which the following is a specification, reference being had to the accompanying drawing, forming part thereof.

The figure is a perspective of a gas stove showing my improved design. When the hinged cover is in its closed position, it has substantially the same appearance as the adjacent stationary top.

I claim:

The ornamental design for a gas stove, as shown and described.

WALTER F. ROGERS.
